UNITED STATES PATENT OFFICE.

GOTTHART TÄUBERT, OF PITTSFIELD, MASSACHUSETTS.

MOLD FOR CONCRETE-WALL CONSTRUCTION.

No. 913,441.

Specification of Letters Patent.

Patented Feb. 23, 1909.

Application filed July 11, 1907. Serial No. 383,267.

To all whom it may concern:

Be it known that I, GOTTHART TÄUBERT, a citizen of the United States, and a resident of Pittsfield, in the county of Berkshire and State of Massachusetts, have invented a new and Improved Mold for Concrete-Wall Construction, of which the following is a full, clear, and exact description.

This invention relates to certain improvements in molds for concrete wall construction, and more particularly to means for holding the mold sections in engagement with the walls and for raising them step by step as the wall is built up. My invention also involves certain construction in collapsible cores to be used in connection with said molds and cooperating with the support for the mold sections to permit the removal of the latter.

20. The invention consists in certain features of construction and combinations of parts, all of which will be fully set forth herein-after and particularly pointed out in the claims.

25. Reference is to be had to the accompanying drawings, forming a part of this specification, in which similar characters of reference indicate corresponding parts in all the figures, and in which—

30. Figure 1 is a top plan view of a wall in process of construction and illustrating one embodiment of my invention; Fig. 2 is a side elevation of one corner of the structure shown in Fig. 1, and on an enlarged scale; Fig. 3 is a transverse section showing the mold and core after having been raised for the construction of a second section of the wall, said view being taken on the line 3—3 of Fig. 4; Fig. 4 is a top plan view showing 40 the mold core and raising mechanism on an enlarged scale; Fig. 5 is an inverted plan view of the core; Fig. 6 is a side elevation partly in section, showing the mold-raising mechanism; Fig. 7 is a plan view of a corner 45 of the wall construction; and Fig. 8 is a transverse section through a modified form of mold designed for giving the completed wall a roughened or rectangular surface.

50. In my improved method of constructing concrete walls, I provide oppositely-disposed mold sections spaced apart to the desired distance and adapted to support and hold the concrete in place while it is hardening to form a wall. Within the mold are provided

cores which serve to form air spaces in the 55 completed wall, and means are provided for raising the mold sections and the core step by step as the wall is built up.

In the specific construction illustrated, each mold section 10 is formed of a substantially rectangular frame 11 of wood or other suitable material reinforced by vertical stay bars 11^a and having a face plate 12 secured thereto and adapted to support the concrete while the latter is hardening. This 60 face plate is preferably of metal and may be either smooth or present a figured uneven or embossed surface of any suitable form to give the finished concrete wall the desired appearance, as illustrated at 12^a in Fig. 8. 70 For supporting and raising the sections, I provide a plurality of vertical standards 13 adapted to be embedded within the wall and extending upright therein intermediate the mold sections. Each upright is somewhat 75 tapered in cross section, as is clearly illustrated in Figs. 4 and 7, and is located adjacent one of the cores, whereby after the wall has been completed to the desired height and the core removed, the upright may be moved 80 laterally into the passage formed by the core and then may be removed entirely from the wall. As illustrated, each standard is provided with oppositely-disposed perforated metal face plates 14, which are engaged by 85 the raising mechanism and serve to protect the wooden body portion of the upright. As shown, the supports for the mold sections comprise a plurality of substantially vertical rods 15, each in rigid engagement with 90 the upper and lower sides of the frames of the mold sections and each having its upper end bent inward to a point adjacent one of the uprights. The two rods are pivoted together at this point and connected to the 95 raising mechanism which surrounds the upright and serves for lifting the latter when a section of the wall has been completed. The rods are connected together at a point adjacent the upper edge of the mold sections, and 100 the connecting mechanism is so constructed as to also serve as means for spreading the sections apart. This connecting mechanism preferably comprises a cross bar 16 having one end pivoted to one of the rods 15, and 105 having the opposite end pivoted to a lever 17, one end of which is pivoted to the oppositely-disposed rod 15. The bar 16 is pivot-

ed to the lever at a short distance from the pivotal support of the latter, and by the movement of the lever the sections may be brought toward each other to the desired 5 position or may be spaced apart and separated from the completed wall. With the lever extending outwardly, as illustrated in Figs. 3 and 4, the sections are held rigid in respect to each other, but when the lever is 10 raised, each of the two sections is moved forward and out of engagement with the wall, the sections being supported by the rods 15, the upper ends of which are connected to the corresponding upright 13. As the upper 15 ends of the rods 15 are connected together and the bar 16 connects them intermediate their ends, it is evident that the lower ends are also held rigid in respect to each other, but to prevent any possible bending of the 20 parts and to hold the lower portion of the mold sections in firm engagement with the portion of the wall just completed, I may, if desired, provide a tie-bar 18 having an operating handle 18^a at one end thereof, and 25 having the opposite end threaded for the reception of a nut in engagement with the opposite mold section. By tightening this tie-bar, the lower ends of the section are positively prevented from spreading apart from 30 the pressure of the concrete.

For raising the mold sections, I provide mechanism in engagement with the upper ends of the rods 15 and with the uprights, and having suitable handles for operating 35 the same, whereby the sections may be readily raised irrespective of the weight thereof. As illustrated, this mechanism comprised a rectangular frame 19 having gripping arms 20 and 21, pivotally connected to the opposite ends thereof, each of the arms inclosing 40 the upright and engaging therewith at the side opposite to its pivotal support. Each arm is provided with an inwardly-directed tooth or projection 22 adapted to enter one 45 of the perforations of the face plates 14 on the uprights, and the upper ends of the two arms are connected together by a suitable coil spring 23. The frame 19 is provided 50 with handles 24 and 25 extending outwardly therefrom in opposite directions, and by means of these handles the frame may be rocked to cause the gripping arms to engage at successively higher points on the opposite sides of the upright, and thus lift the entire 55 raising mechanism and the mold sections connected thereto. The frame 19 is provided with a depending plate 26 at one side thereof, and to this plate are pivotally connected the two oppositely-disposed rods 15. 60 The plate is provided with suitable flanges 27, engaging with the opposite sides of the upright to hold the plate in a substantially vertical position and prevent side movement thereof in respect to the upright.

In the operation of the raising mechanism, the teeth of the two gripping arms engage in recesses in opposite sides of an upright, and by raising one of the handles, as, for instance, the handle 24, the gripping arm 21 is raised along the side of the upright to the position illustrated in dotted lines. During this upward movement of the arm 21 and handle 24, the entire weight of the wall sections is supported by the arm 21. The handle 25 is then raised and the tooth of the arm 21 engages with the upright and the entire wall section is raised and the gripping arm 22 is also raised to a higher point on the side of the upright. Before raising the mold sections, the lower 70 tie-rod 18 is first removed and the lever 17 raised to spread the mold sections apart. When the mold sections have been raised to the desired height, they are again brought toward each other by the lowering of the 75 lever 17 and the lower ends are firmly bound together by the insertion of the tie-rod 18. The small transverse opening left in the wall by the removal of the tie-rod 18 may readily be filled with concrete from both 80 ends thereof to conceal the same from view.

In connection with the mold sections and raising mechanism above described, I preferably provide a plurality of cores serving for the formation of air spaces within the 85 completed wall. The cores may be of any desired shape in cross section, but are preferably formed with rounded ends and straight sides, as illustrated in the drawings. The top of each core is formed of a plate 90 28 of the desired shape, and the sides and ends of the core are preferably formed of sheet metal walls 29 similar to the sheet metal walls of the mold sections. At the bottom of each core, I preferably provide 100 blocks 30, to hold the cores in the desired position, and between the opposite side walls 29 means is provided for drawing these walls together and partially collapsing the core to facilitate the removal thereof from 105 the wall after the concrete has hardened. As illustrated, this collapsing means includes a rod 31 extending vertically through the central portion of the core, and having a plate 32 rigidly secured to the lower end 110 thereof. This plate is provided with two cam slots 33 for the reception of pins 34 carried by the mold sections at their lower ends. By rotating the rod 31 the pins are caused to travel inwardly or outwardly due 115 to the curvature of the slots, and the slots are so formed that the parts will remain in either the extended or the collapsed position. By drawing the side walls of the core together, as illustrated in dotted line in Fig. 120 125 5, the width of the core is reduced to a material extent and the curved end portions of the core are also brought somewhat nearer

together. With the core thus reduced in cross section, it may be readily removed from the hardened concrete about the same and may be readily raised with the mold sections. The upper end of the rod 31 is preferably rigidly connected to a transverse supporting bar 35, which engages with the upper surface of the oppositely-disposed mold sections for supporting the core, and is 10 preferably of spring metal to permit of the raising of the ends of the bar out of engagement with the mold sections to rotate the bar and the rod 31 and to collapse the core.

Where it is desired to form a corner in the 15 wall, I provide means for rigidly securing together the outer mold sections which meet at the angle, and provide means to facilitate the uniting of the inner mold sections at the inner side of the wall. One of the outer 20 mold sections at the corner is provided with perforated lugs 36 at the upper and the lower edges thereof, and the other mold section cooperating therewith to form the corner is provided with locking mechanism 25 adapted for engagement with these lugs. As illustrated in Fig. 2, this locking mechanism comprises two pivoted arms 37 adjacent the upper and the lower sides of the mold sections and each having an outwardly-ex- 30 tending dog or projection adapted for engagement in the perforation of the corresponding projection 36 of the other mold section. To each of the arms is pivotally connected a link 38, and the inner ends of 35 the two links are connected to an oscillating member 39. By oscillating the member 39, the links are drawn inward or forced outward to remove the arms from engagement with the lugs or force them into such engagement to lock the mold sections together or to separate the same. At the inner corner 40 of the wall, each of the inner mold sections is formed of such a length that the sections do not meet when the mold is in place for 45 the reception of the concrete, but the gap between the two ends is closed by a vertically-disposed angle iron 40, as illustrated in Figs. 1 and 7.

To facilitate the removal of the uprights 50 after the wall has been completed to a considerable height, I provide certain of the cores with ends of a slightly greater width than the width of the uprights, and in engagement with the sides of said uprights, as 55 illustrated more clearly in Fig. 7. When the wall has been built up to the height of the upright, the cores adjacent said uprights are entirely removed, and due to the tapered form of the uprights, they may be readily 60 moved laterally into the hollow space in the wall which was formed by the core. The upright may then be raised out of the wall and supported on top thereof to serve for the further raising of the mold sections.

Having thus described my invention, I 65 claim as new and desire to secure by Letters Patent:

1. A mold for concrete wall construction, comprising oppositely-disposed mold sections, an upright disposed therebetween and 70 supporting said sections, and a removable core between said sections, said upright being constructed for lateral movement into the space left by the core.

2. A mold for concrete wall construction, 75 comprising oppositely-disposed mold sections, an upright disposed therebetween and supporting said sections, and a core between said sections, said upright being of greater thickness adjacent one side than adjacent the other and having said side of greatest thickness in engagement with said core, whereby upon the removal of the core the upright may be moved laterally into the space formed by said core. 85

3. A mold for concrete wall construction, comprising oppositely-disposed mold sections, an upright disposed adjacent thereto and supporting said sections, and rods, each having its lower end rigidly secured to one 90 of said sections and having its opposite end pivotally connected to said upright.

4. A mold for concrete wall construction, comprising oppositely-disposed mold sections, an upright disposed therebetween and 95 supporting said sections, rods, each having its lower end secured to one of said sections and having its opposite end pivotally connected to said upright, and means for spreading apart the lower ends of said rods 100 and said mold sections.

5. A mold for concrete wall construction, comprising oppositely-disposed mold sections, an upright disposed therebetween and supporting said sections, rods, each having 105 its lower end secured to one of said sections and having its opposite end pivotally connected to said upright, and means connecting said rods and disposed adjacent the upper edges of said mold sections for spreading 110 said sections and rods apart.

6. A mold for concrete wall construction, comprising oppositely-disposed mold sections, an upright disposed therebetween and supporting said sections, rods, each having 115 its lower end secured to one of said sections and having its opposite end pivotally connected to said upright, a lever arm pivotally connected to one of said rods, a link bar connecting said lever and the other of said rods, 120 whereby one rod and its mold section may be moved in respect to the other rod and its mold section.

7. A mold for concrete wall construction, comprising oppositely-disposed mold sections, an upright disposed adjacent thereto; 125 and raising mechanism including a frame enclosing said upright, arms pivotally con-

4
nected to said frame and in engagement with said upright at the opposite sides thereof, a spring for holding the free ends of said arms in engagement with said upright, means for rocking said frame, and means for operatively connecting said raising mechanism and said mold sections.

8. A mold for concrete wall construction, comprising oppositely-disposed wall sections, an upright disposed therebetween and

serving to support said sections, said upright being laterally movable after the insertion and hardening of the concrete.

In testimony whereof I have signed my name to this specification in the presence of 15 two subscribing witnesses.

GOTTHART TAUBERT.
